UNITED STATES PATENT OFFICE.

CLARENCE W. COLEMAN, OF WESTFIELD, NEW JERSEY, ASSIGNOR TO THE HALL SIGNAL COMPANY, A CORPORATION OF MAINE.

SIGNALING SYSTEM.

No. 872,713.

Specification of Letters Patent.

Patented Dec. 3, 1907.

Application filed June 22, 1906. Serial No. 322,897.

To all whom it may concern:

Be it known that I, CLARENCE W. COLEMAN, a citizen of the United States, a resident of Westfield, county of Union, and 5 State of New Jersey, have invented a Signaling System, of which the following is a specification.

My invention relates to railway signaling systems employing liquefied gas such as carbonic acid gas as the motive power for actuating one or more signals of the system.

One object of my invention is to provide means for actuating a signal by liquefied gas that will avoid leakage of the gas and will 15 thus increase the number of operations of the signal that can be obtained from a given stored supply of gas.

Another object of my invention is to provide means whereby the gas may be utilized 20 to hold a signal at safety without leakage and without consequent alteration of the position of the signal.

Figure 1 illustrates a vertical elevation of my improved signal operating means. Fig. 25 2 is a view of the electromagnet and admission valve used in supplying gas to operate the signal. Fig. 3 is a view of the automatic reducing valve. Fig. 4 is a detail section of the admission valve.

30 The tank 1 contains a local, storage supply of liquefied gas which forms the source of the gas used to operate the signal. The gas contained in the tank 1 is preferably carbonic acid gas at or about the point of liquefaction. In 35 the neck of the tank 1 there is screwed a coupling 2, provided with a valve opening 3, closed by a cap 4 and with a passage 5, the mouth of which can be closed by the screw plug 6.

A gasket 7 and sleeve 8 prevent leakage of 40 the gas, and a sleeve 9 protects the valve stem of the screw plug 6. A passage 10 is connected by the coupling 11 with the pipe 12, which leads to the automatic reducing valve. The pipe 12, by means of the coupling 13, is connected to the branch pipe 14, the branch 15 of which is connected by the screw sleeve 16 to a pipe 17 leading to the high pressure side of the pressure gage 18. One arrow of the pressure gage indicates the 45 high pressure. The gas passes through the pipe 190 and the nipple 19 into the low pressure chamber of the reducing valve. The nipple 19 is ordinarily closed by an automatic valve 20, which is secured by means of 50 screws 21 to a post 22, the post in turn being

secured to a diaphragm 23, which diaphragm forms one wall of the low pressure chamber. The coil spring 24, which may be adjusted by the screw 25, presses against one side of the diaphragm 23. Communication is established between the low pressure chamber and the low pressure side of the pressure gage 18 by means of a pipe 26, the gas passing through opening 27. The low pressure is indicated by the other arrow of the gage 18. 60

The construction of the reducing valve is like that illustrated in the patent to C. W. Coleman, No. 810,262, of January 16th, 1906. From the low pressure chamber of the reducing valve the gas passes through a passage 70 28 into a pipe 29 and may go directly to the means for admitting gas to the signal operating means. The pipe 29 is preferably connected to the expansion chamber 30 by means of the coupling 31, and the expansion 75 chamber is in turn connected to the gas admitting means by the pipe 32.

In order to operate the signal economically and in order to get as many operations as possible out of each tank full of gas, I provide a liquid link or seal, and suitable means whereby the pressure of the gas coming from the liquid supply tank may be transmitted to the liquid to actuate the signal. As shown in Fig. 1, the liquid 33 which is preferably a 80 non-freezing liquid, such as a mixture of alcohol and water, is contained within a chamber having the walls 34 and 35. In the best embodiment of my invention, a diaphragm 36 is interposed between the liquid 33 and 85 the gas pipe 37. Bolts 39, 40 firmly secure the walls 34, 35 and diaphragm 36 together, so as to prevent the leakage of the liquid. 90

In the particular embodiment of my invention illustrated upon the drawings, the 95 chamber having the walls 34, 35, is located at the base of the piston chamber and the piston chamber opens into it.

In the embodiment of the invention illustrated upon the drawings, the reservoir 41 is 100 used to keep the chamber having the walls 34, 35 full of liquid. Should the liquid 33 leak beyond the piston 42, the reservoir 41 will supply enough liquid to keep the chamber full. A pipe 43 leads from the reservoir 105 41 to the liquid containing chamber, and a valve 44 is inserted in said pipe to control the supply of liquid. When the diaphragm 36 is subjected to gas pressure through the pipe 37, the pressure in the diaphragm chamber 110

keeps the valve 37 closed. The piston 42, when gas pressure is applied to the diaphragm 36, rises and moves the signal blade 45 to safety. When the piston 42 returns, 5 the pressure in the pipe 37 having been relieved, free communication exists between the reservoir 41 and the diaphragm chamber, and the reservoir can supply any additional liquid necessary to the chamber.

10 Suitable means are provided which may be widely varied, for admitting gas to actuate the piston mechanism. In the form of the invention illustrated upon the drawings, an admission valve 46 is used to control the 15 admission of gas through the port 47 that leads to the passage 48, which is connected to the pipe 37, at 49. The valve seat 50 is provided for the valve 46, and the valve is guided by guiding means 51, 52. A casing 20 53 is screw-threaded at 54 so as to be removably secured to the body portion in which the valves and passages are located. The inlet pipe 32 supplies gas to the passage 47, through the passageways 55, 56. A screw 25 cap 57 is preferably provided, so that the valve 46 may be gotten out and replaced or adjusted when necessary.

It will be understood that the construction of the valve 46, of the valve chamber, and of 30 the passage ways and accessory parts, may be widely varied. In the form of the invention illustrated upon the drawings, the valve 46 is connected by means of a stem 58 to an 35 exhaust valve 60, so that the admission valve and exhaust are operated simultaneously. The exhaust passage 61 leads to the atmosphere.

Suitable means are provided for actuating 40 the valve 46. As illustrated, a valve stem is pivotally connected at 62 to lever 63, one 45 end 64 of the lever, being secured to a rod 65 which may be adjusted by means of the screw-threaded portion 66 and nuts 67. The other end of the lever 63 is connected to the 50 valve operating means by a link 68, provided with an adjustable connection 69.

In the particular embodiment of my invention illustrated upon the drawings, an electromagnet 70 is used to operate the bell 55 crank armature 71, one arm of the bell crank being secured to the link 68 through the adjustable connection 69. Screws 72 serve as 60 pivots for the bell crank.

The means for controlling the electromagnet 70 may be widely varied. I have shown 55 for this purpose an electric battery 73, and an electric circuit 74, that includes the electromagnet 70. A circuit closer 75 makes and breaks the circuit 74 so as to energize 60 and deenergize the electromagnet 70. The means for operating this circuit closer may be widely varied. As illustrated, a track circuit 76, with track battery 77, is provided, the current from the battery 77 energizing 65 the coils of the relay magnet 78. When so

energized, the relay 78 attracts the circuit closer 75 and closes the circuit. When the train 79 is on the track 76 it prevents the current from passing through the track relay 78, and the circuit closer 75 is opened by the 70 spring 80.

When the magnet 70 is energized, the admission valve 46 is opened, and the exhaust valve 60 is closed and the gas entering below the diaphragm 36, through the pipe 37, sends 75 the signal to safety. No train is then on the section protected by the signal. When the magnet 70 is deenergized, the admission valve closes and the exhaust valve opens, and the signal goes to danger behind the 80 train on the section. The signal blade 45 is connected to the piston 42 by means of connecting rod 81. The piston 42 is provided with a stem 82, which is guided through the cap 83 that closes the cylinder. 85

With the above description of my invention and the operation already given, the operation of the various parts will be readily understood. My invention may be applied to normal danger as well as to normal safety 90 systems. In the drawings, my invention is shown in connection with a normal safety system.

My invention in its broader aspects is not limited to the particular construction and 95 relative arrangement of the parts herein shown and described nor to any particular form of apparatus by which the invention may be carried into effect, as many changes may be made in the construction and relative arrangement of the parts as required 100 to adapt the apparatus to the circumstances of the personal views of the engineer employed to carry the invention into effect without departing from the main principles 105 of the invention and without sacrificing its chief advantages.

Having thus described my invention, what I claim and desire to secure by Letters Patent, is:

1. In a railway signaling system, the combination of a signal normally biased to danger, a local tank for liquefied gas, a liquid link, a track circuit and means controlled by said track circuit whereby the pressure of the 115 gas may be transmitted to the liquid to actuate the signal.

2. In a railway signaling system, the combination of a signal normally biased to danger, a local tank for liquefied gas, a liquid link, means for replenishing the supply of liquid, a track circuit and means controlled by said track circuit whereby the pressure of the gas may be transmitted to the liquid to actuate the signal. 120

3. In a railway signaling system, the combination of a signal normally biased to danger, a local tank for liquefied gas, a liquid link, a diaphragm between the gas and the liquid, a track circuit and means controlled 130

by said track circuit whereby the pressure of the gas may be transmitted through the liquid to actuate the signal.

4. In a railway signaling system, the combination of a signal normally biased to danger, a local tank for liquefied gas, a piston, a piston chamber, a chamber for containing liquid located at the base of said piston chamber and into which said piston chamber 10 opens and means whereby the pressure of the gas may be transmitted to the liquid to actuate the signal.

5. In a railway signaling system, the combination of a signal normally biased to danger, a local tank for liquefied gas, a piston, a piston chamber, a chamber for containing liquid located at the base of said piston chamber and into which said piston chamber opens, a diaphragm in said chamber, and 20 means whereby the pressure of the gas may be transmitted to the liquid to actuate the signal.

6. In a railway signaling system, the combination of a signal normally biased to danger, a local tank for liquefied gas, a piston, a piston chamber, a chamber for containing liquid located at the base of said piston chamber and into which said piston chamber opens, a diaphragm in said chamber, a reservoir for supplying liquid to said chamber, a valve between said reservoir and said chamber and means whereby the pressure of the gas may be transmitted to the liquid to actuate the signal.

35 7. In a railway signaling system, the combination of a signal normally biased to danger, a local tank for liquefied gas, a piston, a piston chamber, a chamber for containing liquid located at the base of said piston 40 chamber and into which said piston chamber opens, a diaphragm in said chamber, a reservoir for supplying liquid to said chamber, an automatic check valve between said reservoir and said chamber and means whereby 45 the pressure of the gas may be transmitted to the liquid to actuate the signal.

8. In a railway signaling system, the combination of a signal normally biased to danger, a local tank for liquefied gas, a liquid 50 link, a diaphragm between the gas and the liquid, an admission valve, an electromagnet for actuating said valve, and means for controlling said magnet.

9. In a railway signaling system, the combination of a signal normally biased to danger, a local tank for liquefied gas, a reducing valve for reducing the pressure of the gas, an admission valve, an electromagnet for controlling said admission valve, a piston and 60 piston chamber for actuating said signal, and a chamber for containing liquid located at the base of said piston chamber and into which said piston chamber opens.

10. In a railway signaling system, the combination of a signal normally biased to dan-

ger, a local tank for liquefied gas, a piston and piston chamber, a chamber for containing liquid into which said piston chamber opens, said chamber being of larger cross-section than said piston chamber and located at the base of said piston chamber, a movable member adapted to transmit pressure to the liquid, and means for subjecting said member to gas pressure, whereby the signal may be moved to safety. 75

11. In a railway signaling system, the combination of a signal normally biased to danger, a local tank for liquefied gas, a piston and piston chamber, a chamber of larger cross-section than said piston chamber, into which said piston chamber opens, adapted to contain liquid and located at the base of said piston chamber, a diaphragm, the area of said diaphragm exceeding that of said piston, the parts being so constructed and arranged that a small movement of the diaphragm may be utilized to give a greater movement to said piston, and means whereby the pressure of the gas may be transmitted to the diaphragm. 90

12. In a railway signaling system, the combination of a signal normally biased to danger, a local tank for liquefied gas, a piston and piston chamber, a chamber for containing a substance which readily changes its form so as to pass into and out of said piston chamber, said chamber being of larger cross-section than said piston chamber and located at the base of said piston chamber, a movable member adapted to transmit pressure to the substance, and means for subjecting said member to gas pressure whereby the signal may be moved to safety. 95

13. In a railway signaling system, the combination of a signal normally biased to danger, a local tank for liquefied gas, a piston and piston chamber, a chamber of larger cross-section than said piston chamber into which said piston chamber opens, and adapted to contain a substance which changes its form so as to pass into and out of the piston chamber, said chamber being located at the base of said piston chamber, a diaphragm, the area of said diaphragm exceeding that of said piston, the parts being so constructed and arranged that a small movement of the diaphragm may be utilized to give a greater movement to said piston, and means whereby the pressure of the gas may be transmitted to the diaphragm. 110

14. In a railway signaling system, the combination of a signal normally biased to danger, a local tank for liquefied gas, a piston and piston chamber, a chamber for containing a substance which readily changes its form so as to pass into and out of said piston chamber, said chamber being of larger cross-section than said piston chamber and located at the base of said piston chamber, a movable member adapted to transmit pressure to the 115 120 125 130

substance, a track circuit and means controlled by said track circuit whereby the pressure of the gas may be transmitted to the substance to actuate the signal.

- 5 15. In a railway signaling system, the combination of a signal normally biased to danger, a local tank for liquefied gas, a piston and piston chamber, a chamber of larger cross-section than said piston chamber into
- 10 which said piston chamber opens, and adapted to contain a substance which changes its form so as to pass into and out of the piston chamber, said chamber being located at the base of said piston chamber, a diaphragm, the area of said diaphragm exceeding that of
- 15 said piston, the parts being so constructed and arranged that a small movement of the diaphragm may be utilized to give a greater movement to said piston, a track circuit and

means controlled by said track circuit where- 20 by the pressure of the gas may be transmitted to the substance to actuate the signal.

16. In a railway signal system the combination of a series of insulated track sections, a series of normally closed circuits, each in- 25 cluding a track section, a series of signals normally held at danger indication, and for each such signal a piston and piston chamber, a liquid link in said chamber and means for transmitting pressure through said liquid to 30 actuate said signal.

In testimony whereof, I have signed my name to this specification, in the presence of two subscribing witnesses.

CLARENCE W. COLEMAN.
